UNITED STATES PATENT OFFICE.

ALFRED TERHUNE, OF PATERSON, NEW JERSEY.

DESIGN FOR A TAG-FASTENER.

SPECIFICATION forming part of Design No. 25,756, dated July 7, 1896.

Application filed April 11, 1896. Serial No. 587,231. Term of patent 7 years.

To all whom it may concern:

Be it known that I, ALFRED TERHUNE, a citizen of the United States, residing in Paterson, Passaic county, State of New Jersey, have invented and produced a new and useful Design for Tag-Fasteners; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to a new design for tag-fasteners, as hereinafter set forth and claimed, and which is illustrated in the accompanying drawings.

Figure 1 represents a top plan view of a tag-fastener, showing my design; and Figs. 2 and 3, sectional views on the lines *x-x* and *y-y* of Fig. 1, respectively.

a is the tag-fastener, having the substantially parallel sides *c c* connected at one end

by the semicircular side *b* and at their other ends by the straight sides *d*, tapering to a point *e*.

The tag-fastener which in top plan view, Fig. 1, has a pen-shaped appearance is concave, that is to say, is slightly curved when viewed in longitudinal or transverse section, as shown at *a'* in Figs. 2 and 3, and is provided at the highest and substantially central portion with a round or oval aperture *f*.

Having thus described my invention, what I claim as new, and desire to secure by Letters Patent, is—

The design for a tag-fastener, substantially as shown and described.

In testimony that I claim the foregoing I have hereunto set my hand this 8th day of April, 1896.

ALFRED TERHUNE.
